CLAIM

We claim, the ornamental design for a shield, as shown and described.

DESCRIPTION

FIG. 1 is a top perspective view of a shield in accordance with the present invention.

FIG. 2 is a rear perspective view thereof.

FIG. 3 is front view thereof.

FIG. 4 is a rear view thereof.

FIG. 5 is a side view thereof.

FIG. 6 is a side view thereof.

FIG. 7 is a top plan view thereof.

FIG. 8 is a bottom view thereof.

FIG. 9 is a top perspective view thereof.

FIG. 10 is a rear perspective view of an alternative embodiment of the present invention.

FIG. 11 is a front view of said alternative embodiment.

FIG. 12 is a rear view of said alternative embodiment.

FIG. 13 is a side view of said alternative embodiment.

FIG. 14 is a side view of said alternative embodiment.

FIG. 15 is a top plan view of said alternative embodiment; and,

FIG. 16 is a bottom view of said alternative embodiment.
